Switzerland

Application March 8, 1935, Serial No. 10,081
In Switzerland March 13, 1934

18 Claims. (Cl. 230—56)

The present invention relates to a united reciprocating internal combustion engine and compressor of the floating piston type having a plurality of power and compressor cylinders for generating hot high pressure gases which may be used for operating, for example, a gas turbine and for producing compressed air which is used as combustion air in said apparatus and/or may also be used for other purposes, more particularly to methods and apparatus for synchronizing the operation of the individual pistons and for controlling the stroke of the individual pistons.

An object of the present invention resides in the provision of a hook-up between the pistons operating in different cylinders of a united reciprocating internal combustion engine and compressor having floating pistons, whereby, at a change of the length of the stroke of the pistons operating in one cylinder, the length of the stroke of the pistons operating in another cylinder is automatically changed, too.

A further object of the present invention is the provision of a hydraulic or pneumatic coupling between pistons operating in different cylinders of a united reciprocating internal combustion engine and compressor, whereby the length of the stroke of various floating pistons operating in different cylinders can simultaneously be changed by adding operating medium to or by withdrawing it from the hydraulic or pneumatic coupling.

Another object of this invention is to provide a hydraulic or pneumatic coupling between pistons operating in different cylinders of a united reciprocating internal combustion engine and compressor, whereby the length of the stroke of various floating pistons operating in different cylinders is automatically maintained by automatically adding operating medium to or by withdrawing it from the hydraulic or pneumatic coupling.

A further object of this invention is the provision of an engine having floating pistons, the end of the stroke of which is determined by the pressure of a medium compressed in the clearance of the cylinders in which the floating pistons operate, and of supplementary cushioning means adapted to check the movements of the floating pistons and to adjust their position at the end of a stroke.

A further object of this invention is to provide a unified internal combustion-compressor engine having floating pistons and in which the power and compressor pistons are directly connected and in line with one another and in which also the power and compressor cylinders are directly connected and in line with one another, and of means assuring that, when the stroke of a combined power and compressor floating piston is changed, the stroke of the power piston is

changed to a length different from that of the compressor piston.

An object of this invention is the provision of a unified internal combustion-compressor engine having floating pistons comprising a plurality of unified power and compressor cylinders and a coupling adjustably interconnecting the floating pistons operating in different cylinders and adapted to change the stroke of the pistons operating in different cylinders in dependence on an operating characteristic of said unified internal combustion-compressor engine.

Further and other objects of the present invention will be hereinafter set forth in the accompanying specification and claims and shown in the drawings which, by way of illustration, show what I now consider to be a preferred embodiment of my invention.

In the drawings:

Fig. 1 is a diagrammatic showing of a power and compressed air producing plant according to my invention.

Fig. 2 is a crank diagram of an engine as illustrated in Fig. 1.

Fig. 3 is another crank diagram of an engine as shown in Fig. 1.

Fig. 4 is a diagrammatic showing of another embodiment of my invention.

Fig. 5 shows a variation of the plant illustrated in Fig. 4.

Fig. 6 is a diagrammatic showing of a detail of the plant illustrated in Figs. 4 and 5.

Fig. 7 is a diagrammatic showing of a variation of the detail shown in Fig. 6.

Fig. 8 shows indicator diagrams of engines according to my invention and forming the principal part of the plants shown in Figs. 1, 4, and 5.

Fig. 9 shows another variation of the plant shown in Fig. 4.

Like parts are designated by like numerals in all figures of the drawings.

Referring more particularly to Fig. 1 of the drawings: 1 and 2 are the power pistons operating within combustion cylinder 5; 3 and 4 are power pistons operating within combustion cylinder 6. To the ends of combustion cylinder 5, compressor cylinders 7 and 8 are attached and, to the ends of combustion cylinder 6, compressor cylinders 9 and 10. Compressor pistons 11, 12, 13, and 14 are connected to the power pistons 1, 2, 3, and 4, respectively. Combustion and scavenging air is conducted into cylinder 5 through conduit 15 and into cylinder 6 through conduit 16. Fuel is introduced into cylinder 5 through feeder 17 and into cylinder 6 through feeder 18. These feeders are not shown in detail as they are not part of the present invention. The exhaust gases of cylinder 5 are removed through conduit 19 and those of cylinder 6 through conduit 20. Both conduits may be con-

nected to a conduit 89 which conducts the exhaust gases of cylinders 5 and 6 into a gas turbine 90. The gas to be compressed, for example air, is drawn into single acting compressor cylinders 7 and 9 from filter 80 through duct 21 and into single acting compressor cylinders 8 and 10 from filter 81 through duct 21'. The air compressed in cylinder 7 passes through duct 22 into receiver 82 and therefrom through conduit 15 into cylinder 5 serving as charging and scavenging air. Likewise, the air compressed in cylinder 9 passes through conduit 22' into receiver 83 and therefrom through conduit 16 into cylinder 6. The air compressed in cylinders 8 and 10 passes through conduits 84 and 85 into common receiver 86 and therefrom to consumers, for example, pneumatic hammer 87 and/or compressed air turbine 88.

A rod 23 is connected to compressor piston 11, 20 a rod 25 to piston 13, a rod 24 to piston 12, and a rod 26 to piston 14. These piston rods are each movably connected with a connecting rod, namely, 23 with 27, 25 with 29, 24 with 28, and 26 with 30. Connecting rods 27 and 29 operate 25 crank shaft 31, and connecting rods 28 and 30 operate crank shaft 32. The individual cranks on each shaft and the cranks of two different shafts but associated with the same cylinder are set at an angle of 180° with respect to one another so that the pistons associated with the cranks move in opposite directions. The radius of the cranks may be made so large as compared with the stroke of the pistons that the crank shafts do not rotate but carry out a swinging 35 motion, whereby the cranks never reach the crank dead center position proper. Crank shafts 31 and 32 may be coupled together by means of bevel gears 109, 111 and 110, 112 and shaft 113 arranged between these gears, whereby the counter- 40 movement of the pistons in the individual cylinders is synchronized.

It is of advantage to make the length of the connecting rods as small as possible as compared with the radius of the associated cranks because, 45 with such a construction, a change of the position of a power piston at the end of its compression stroke entails only little change of the position at the end of the compression stroke of the associated compressor piston. This is obvious 50 from Fig. 2. If the swing of the crank shaft is reduced from angle α to angle β , the stroke of the united power and compressor piston is reduced from value a to value b ; the position of the power piston at the end of its compression 55 stroke is changed by the distance d , whereas the position of the compressor piston at the end of its compression stroke is changed by the shorter distance c . The shorter the connecting rod, the greater is the difference between d and c . In 60 this way, even a great change of the position of the power pistons at the end of their compression stroke has but little effect on the position of the associated compressor pistons at the end of their compression strokes and has but little effect 65 on the pressure of the gas compressed in the compressor cylinders. Fig. 3 diagrammatically shows an arrangement in which the crank passes outer dead center position, and the connecting rod 28 moves on both sides of the center line of the cylinder so that, for each position of the piston, two positions of the connecting rod are possible, whereas, in the arrangement shown in Fig. 2, the connecting rod 28 moves always on one side of the center line of the cylinder, and only one 70 position of the connecting rod is possible for each

position of the piston. For an operation according to the diagram Fig. 3, the crank shafts 31 and 32 are provided with fly wheels 122 and 123 so that the crank shafts swing beyond dead center position as diagrammatically shown in Fig. 3. If the extent of the swing of a shaft is reduced from the value γ in Fig. 3 to value δ , the inner dead center position of the piston associated with this crank is changed by the distance e , whereas the outer dead center position is not changed at all. 10

The operation of the apparatus according to Figs. 1 and 3 is as follows:

If more power is required from gas turbine 90, more fuel is supplied through nozzles 17 and 18. The supply of fuel may be adjusted by hand 15 or automatically; this adjustment per se is not part of the present invention. An increased fuel supply to cylinders 5 and 6 causes increased pressure within these cylinders and a shortening of the compression stroke of the power pistons. 20 Before the increase of fuel supply, shaft 32 swings, for example, as far as angle γ in Fig. 3; after the increase of the fuel supply, the shaft only swings as far as the smaller angle δ in Fig. 3, and the stroke of a combined power and compressor piston is decreased by the distance e , and the space available for combustion is increased accordingly. The work done per stroke of a power piston is thereby considerably increased as is obvious from and will be described 25 later in connection with the diagram Fig. 8. As soon as more power is available from the power pistons, the movement of said pistons is sped up and more air is compressed per time unit; as long as the consumption of gases produced in 30 the combustion cylinder and/or the amount of compressed air required for purposes other than combustion purposes is not increased, higher pressure in the air compressors associated with the combustion cylinders and of the charging and 35 scavenging air is obtained automatically. As is also obvious from the diagrams Fig. 8, a shortening of the suction stroke of the air compressor pistons is of little influence on the air pressure obtained, and it is desirable to maintain 40 the outer dead center position of the associated pistons 1, 11, 2, 12, 3, 13, and 4, 14 and to arrange for wide variations of the inner dead center positions in order to obtain highest efficiency in the 45 operation of the power part as well as of the compressor part of the engine. This condition is assured by a machine according to Fig. 1 of the drawings to a great extent if operated according to Fig. 3 and, to a modified extent, if operated according to Fig. 2. 50

In the embodiment of my invention illustrated in Fig. 4 of the drawings, the pistons are pair-wise interconnected by means of a combined hydraulic and mechanical coupling. As far as the power cylinders and power pistons and the compressor cylinders and compressor pistons are concerned, the arrangement is the same as the one shown in Fig. 1. The compressor piston 11 carries, by means of an extension rod 35, an auxiliary piston 36; in like manner, piston 13 carries auxiliary piston 38; piston 12 carries piston 37 by means of rod 35', and piston 14 carries auxiliary piston 39 likewise. A conduit 33 containing a liquid or gaseous operating medium connects pistons 36 and 38, and a conduit 34 also carrying a liquid 60 or gaseous operating medium operatively connects pistons 37 and 39. Control device 40 is arranged in conduit 33 and a like device 41 in conduit 34; the purpose of said devices is to control addition of operating medium to and with- 65 70 75

drawal of operating medium from conduits 33 and 34. Pistons 36 and 38 each carry a piston rod 36' and 38', respectively, the ends of which are individually movably connected to the ends of two-arm lever 42. The fulcrum 44 in the center of lever 42 is carried by slide valve 46. Likewise, pistons 37 and 39 carry two-arm lever 43, the fulcrum 45 of which is carried by slide valve 47. Valve 46 moves within cylinder 51 having ports 48, 49, and 50. Cylinder 51 slidably moves within the cylindrical casing of device 48 against the tension of spring 52 and under the action of a control fluid introduced through conduit 53. A like cylinder is provided in control device 41 which may be actuated by a control fluid introduced through conduit 53'. Conduits 53 and 53' are connected by means of conduit 114 with the air chamber supplying the inlet ports 115 of cylinder 6 with scavenging and combustion air. The operation of cylinders 51 is thus made dependent upon the pressure of the charging and scavenging air.

If the pressure of the scavenging and charging air goes up, valve cylinder 51 is moved upwards—as viewed on Fig. 4—; openings 49 and 50 are then free, and coupling medium contained in conduit 33 exits through outlet 55; pistons 1, 11 and 3, 13 therefore move further outwards, whereby the clearance in cylinders 7 and 9 is reduced, and the volume available for air compression in said cylinders is reduced; this causes a decrease of the pressure of the charging and scavenging air—a result which was desired.

The outward movement of pistons 1, 11, 36, 35 and 3, 13, 38 also causes an outward movement of valve 46, whereby opening 50 is closed again so that equilibrium is restored and outflow of too much medium out of conduit 33 is prevented.

If the pressure in chamber 115 decreases, piston 51 moves downwards—as viewed in Fig. 4—and opening 50 is closed, whereas opening 48 is opened permitting an inflow of medium through conduit 54 into conduit 33; pistons 36 and 38 are pressed downwards—as viewed in Fig. 4—and therewith piston sets 1, 11 and 3, 13; this causes an increase of the clearance in cylinders 7 and 9 and an increase of the volume available for air compression in said cylinders and a rise of pressure of the supercharging and scavenging air. Inward movement of pistons 1, 11, 36 and 3, 13, 38 causes also inward movement of valve 46 and a closing of opening 48, whereby inflow of too much medium into conduit 33 is prevented and equilibrium is restored.

In the embodiment of my invention according to Fig. 5, conduits 53 and 53' are connected by means of a conduit 117 with chamber 118 receiving the exhaust gases of cylinder 6, and the operation of cylinders 51 and the adjustment of the length of the columns of liquid in conduits 33 and 34 are made dependent on the back pressure of cylinder 6.

The operation of the arrangement according to Fig. 5 is like the operation described in connection with Fig. 4, with the exception that whereas by the arrangement according to Fig. 4 the pressure of scavenging and charging air entering cylinders 5 and 6 is maintained constant, in the arrangement according to Fig. 5 the pressure of the gases leaving cylinders 5 and 6 is maintained.

The extent of the movement of cylinder 51 may be limited and manually adjusted by operating spindle 119 extending through cover 118 of body 40 and having a hand wheel 120. A similar adjusting means 119' and 120' may be associated

with control device 41. These manual adjusting means may serve solely for adjusting the length of the columns of conduits 33 and 34 or may be used in connection with the pressure control actuated by the fluid pressure in conduits 53 and 53'. 5

When operating the floating piston power plant, the pistons in cylinders 5 and 6 are alternately driven apart under the influence of the expanding combustion gases, and air is simultaneously compressed in cylinders 7, 8, 9, and 10. The air compressed in cylinders 7 and 8 goes through conduits 95 and 96 into receiver 97 and therefrom as combustion and scavenging air through conduit 15 into power cylinder 5. The air compressed in cylinders 9 and 10 goes through conduits 98 and 99 into receiver 100 and therefrom as combustion and scavenging air through conduit 16 into cylinder 6. The combustion gases leave cylinder 5 after expansion therein through conduit 101 and are further used to drive the gas turbine 103. 20 The gases exhausting from cylinder 6 are likewise conducted through conduit 102 into a turbine 104. Conduits 101 and 102 may be interconnected by tube line 105 having a stop valve 106 for separating or interconnecting conduits 101 and 102. In the arrangements shown in Figs. 4 and 5, much more air may be supplied to the power cylinders than is needed for burning up the fuel. A part of the air, therefore, passes through cylinders 5 and 6 and serves for cooling 30 the exhaust gases, whereby the life of the gas turbines is prolonged and their efficiency increased.

The movement of the pistons is checked in the extreme outer positions by the pressure of the 35 air cushions created during the outward movement of the pistons. At the following period of operation, the pistons are moved back pairwise into center position by the action of the piston pair which carries out an expansion stroke, said 40 action being transmitted through the medium in conduits 33 and 34. At an inward movement of the compressor pistons, air is drawn into the compressor cylinders from conduits 21 and 21'. At the same time, the scavenging air and combustion 45 air entering cylinders 5 and 6 through conduits 15 and 16, respectively, is compressed by action of the power pistons moving towards the center of their cylinder. The expansion of the gases resulting from the combustion of the fuel introduced through feeders 17 and 18 drives the pistons 50 apart, and the cycle of operation starts anew.

The stroke of the power and compressor pistons depends on the extent to which conduits 33 and 34 are filled with operating medium. This filling 55 is controlled by means of the devices 40 and 41 as has been described before.

In order to also synchronize the movement of the pistons countermoving in the same cylinder, a double acting piston 56 may be introduced into 60 conduit 33 and a similar piston 57 into conduit 34 which operate pistons 68 and 61, respectively. Pistons 68 and 61 are adapted to reciprocatingly move in cylinders 63 and 63', respectively which form part of the conduit 62 and are operatively 65 interconnected by a gaseous or liquid medium enclosed in conduit 62. One of the cylinders 63 and 63'—in the case illustrated, cylinder 63—points in the direction of piston 56, while the other points in opposite direction giving conduit 70 62 with its cylinders 63 and 63' the configuration of a Z and assuring that both pistons 68 and 61 move in the same direction, whereas pistons 1 and 2 and also pistons 3 and 4 move in opposite directions. A relief valve 64 may be provided 75

in connection with conduit 62 which allows operating medium to escape if the pressure within conduit 62 is too high, for example, when a piston 60 or 61 gets jammed and the other piston is still 5 in motion. Furthermore, a conduit 65 with a check valve 66 may be provided through which supplementary operating medium may be supplied to conduit 62 to make up leakage losses and the like. Should the provision of conduit 62 10 in connection with single acting pistons 60 and 61 not suffice to assure a rigid and positive synchronizing action, a conduit 62' may be provided to interconnect the other sides of pistons 60 and 61 and also be filled with operating medium; 15 such a conduit would assure an absolutely rigid operation.

If the gas cushion in the compressor cylinders is not sufficient to limit the stroke of the pistons, an additional hydraulic damper may be associated with each of the pistons 36, 37, 38, and 39 20 by providing each piston with an extension 67 which, at the end of an outward piston stroke, is inserted into a corresponding recess 69 of plug 68 extending into the interior of conduit 33. The 25 operating medium contained in recesses 69 is compressed to a certain degree which depends, for example, on the amount of fuel introduced into the combustion cylinders. If much fuel is introduced, the pistons are thrown outwards with 30 great force, and piston 67 creates great pressure in recess 69, operating medium may escape, and the pressure be relieved through a conduit 70. Such a damper is illustrated in larger scale in Fig. 6 of the drawings. Conduit 70 permits constant 35 leakage of operating medium; the bore of said conduit is very small as compared with the size of chamber 69, and the amount of leakage is very small; as soon as larger amounts pass through conduit 70, the velocity of the fluid and the frictional resistance within the channel is considerably increased, and outflow of excessive amounts is prevented. Only if the pressure is very high, which is the case when piston 67 enters chamber 69, larger amounts are pushed through channel 70 40 and this is desirable because in this manner excessive pressure in chamber 69 is relieved. A pressure relief valve 70' may be connected to conduit 70 which then can have a larger bore.

When more work is done in cylinders 5 and 6 45 because of an increase of the interior volume and capacity of the cylinders caused by an outward movement of the outer dead center position of the pistons, it may be necessary that the clearance in the compressor be reduced so that its capacity 50 increases; this is particularly important if it is desired that the pressure of the compressed gas or air remain constant. For this purpose, a damper as shown in Fig. 7 may be provided for the pistons 36, 37, 38, and 39 in Fig. 4 which are 55 each provided with an extension 71 and which, together with the lower end of cylindrical cages 72, enclose a chamber 73, the position of which can be changed by adapting cages 72 to be moved in the direction of the axes of pistons 36, 37, 38, or 60 39, respectively. Such change of position of cages 72 can be effected by providing a thread 74 in the upper center part of cage 72 which also serves as a gland for the rods connecting pistons 36, 37, 38, and 39 with the double levers 42 and 43, as 65 was previously described, and by also threading the part pertaining to conduit 33 or 34, shown in Figs. 4, 5, and 9, adjacent to said center part, so that cage 72 may be screwed up and down. A channel 75 may be provided in cage 72 corresponding to channel 70 in Fig. 6 for relieving the 70 75

operating medium from space 73. This channel 75 operates in the same manner as does the channel 70 in Fig. 6. A pressure relief valve 75' may be provided to act in the same manner as valve 70' of Fig. 6.

The operation of an arrangement according to Figs. 4 to 7 with respect to the dead center positions of the pistons is like the operation of the arrangement according to Fig. 1 and operating as per diagram Figs. 2 or 3. Whereas in the 10 arrangement according to Fig. 1 the outer dead center positions of the pistons are little or not at all changed, at a change of the inner dead center positions due to the particular swinging motion demonstrated in Figs. 2 and 3 the outer dead 15 center positions of the pistons in arrangements according to Figs. 4 to 7 are held substantially constant because the outward movement of the pistons is positively terminated by the air compressed in the compressor cylinders and/or the 20 medium compressed in chambers 69 and 73.

In order to demonstrate the effect of a change of the inner dead center positions and the maintenance of the outer dead center positions of the pistons in the arrangements according to Figs. 1 to 7, diagrams Fig. 8 have been plotted.

The upper part of Fig. 8 shows indicator diagrams of the combustion cylinders 5 and 6. The dotted line diagram shows the conditions with far inwards moving pistons as is the case when 30 shaft 32 swings around angle α in Fig. 2 or angle γ in Fig. 3. Charging pressure and compression pressure are small and the volume V_0 available for combustion amounts to only 6% of the total volume available for the expansion stroke. The solid 35 line diagram shows the conditions with the inner dead center position of the piston further out as is the case when shaft 32 swings around angle β in Fig. 2 or angle δ in Fig. 3. Charging pressures and compression pressures are high and the combustion volume V_1 amounts to 13% of the total 40 expansion volume.

The lower part of Fig. 8 shows two indicator diagrams of the compressors corresponding to the operating conditions of the power pistons 45 shown in the upper part of Fig. 8. In both cases, the compression volume V_c is approximately the same, whereas the compression pressure—in the case of the dotted line diagram—amounts to 1.2 atmospheres and—in the case of the solid line 50 diagram—amounts to 4.0 atmospheres.

The upper diagrams of Fig. 8 which represent indicator diagrams taken in the combustion or power cylinders show that an increase of the combustion space at the inner dead center position 55 of the power pistons together with an increase of the fuel supply greatly increases the work per stroke of the power pistons which is represented by the area enclosed by the indicator diagrams; the work available for air compression is, of course, also increased; the lower diagrams of Fig. 8 which represent indicator diagrams taken in the air compressor cylinders show that a change of the inner dead center position—which is represented by the left side of Fig. 8—of the air compressor piston has little effect on the work required by the compressor which is represented by the area enclosed by the indicator diagrams, whereas, for example, an outward movement of the outer dead center position of the air compressor pistons would greatly increase the area of the indicator diagrams and the work required by the compressor; if this increased work is not supplied, the height of the diagram and the pressure of the compressed air are reduced.

In the embodiment of my invention according to Fig. 9, valve cylinders 51 inside of control means 40 and 41 and illustrated in Fig. 4 are made responsive to the amount of fuel supplied to power cylinder 6, and the fuel injection is made dependent on the charging pressure of the power cylinder and also on the stroke of a floating piston. For the latter purpose, compressor piston 13 carries a bolt 124 which abuts, at the 10 end of an inward stroke of the piston, against one arm of bell crank lever 125. The other arm of this lever is adapted to adjustingly abut, by means of adjusting screw 140, against the end of lever 141 to which fuel valve 126 is connected. 15 Upon abutment of lever 125 against lever 141, the fuel valve is lifted against the action of spring 142, and fuel oil supplied by rotary pump 128 is admitted to cylinder 6. When valve 126 is closed, the fuel oil passes through constant pressure relief valve 130 and conduit 129 back into tank 132. The extent of the fuel admission stroke of valve 126 is further controlled in dependence on the pressure of the scavenging air in chamber 133. For this purpose, chamber 133 20 is connected by conduit 134 with cylinder 135 containing piston 136 which may be moved downwards, as viewed in Fig. 9, by action of the pressure of the scavenging air and against the action of spring 131. A rod 94 is connected to piston 25 136 and movably carries arm 137, to the free end of which eccentric 138 forming the fulcrum of bell crank lever 125 is connected. Fuel injection is advanced or retarded according to the position of eccentric 138. The stem of valve 126 carries 30 a piston 143 operating in cylinder 144, the interior of which is connected with the interior of casings 40 and 41 by means of conduits 145, 53, and 53'. These conduits and the cylinders connected thereto are filled with an actuating medium, for example, air which transmits movements 35 of piston 143 to valve cylinders 51. In this manner, the position of cylinders 51 is made dependent on the position of valve 126, i. e., if this valve is lifted to a great extent, cylinder 51 is also 40 lifted to a great extent; the more dense the operating medium in conduits 53, 53', and 145, the more pulsating will be the operation of cylinder 51; the extent of movement, however, is always 45 in proportion to the extent of the opening of fuel valve 126 and the movements of cylinder 51 are thus made dependent on the amount of fuel supplied to power cylinder 6.

For example, if more power is required from gas turbine 104', more operating gas is demanded 50 from and the pressure in cylinder 6 goes down upon withdrawal of more gas therefrom; as a result piston 3, 13 will move further inwards and, with it, pin 124; this causes an increase of the stroke of fuel valve 126, of the fuel supply to 55 cylinder 6, and of the pressure and amount of gas produced to operate turbine 104'. A decrease of the back pressure in cylinder 6 also causes an upward movement of piston 136—as viewed on Fig. 9—which also causes an increase of fuel 60 supply to cylinder 6 as has been described in the paragraph next above. When the fuel supply is increased, a larger space for combustion within cylinder 6 is desired, i. e., a reduction of the inward movement of piston 3, 13. This is effected 65 by reducing the content of operating medium within conduit 33. At an increase of the lift of fuel valve 126, valve cylinder 51 is moved upwards—as viewed on Fig. 9—causing an opening of port 58 and permitting an outflow of operating 70 medium from conduit 33 through ports 49 and 59

and conduit 55. This reduction of the content of conduit 33 entails also a lifting—as viewed on Fig. 9—of fulcrum 44 and valve 46 and a closing of port 58, whereby equilibrium is restored.

While I believe the above described embodiments of my invention to be preferred embodiments, I wish it to be understood that I do not desire to be limited to the exact details of method, design, and construction shown and described, for obvious modifications will occur to a person skilled in the art.

What is claimed is:

1. In a united reciprocating power and compressor engine, a power cylinder extending at one end into a compressor cylinder, a floating piston in said cylinder, said floating piston comprising a compressor piston operating in said compressor cylinder and a power piston in said power cylinder, pressure responsive means operatively associated with said floating piston and said power cylinder and being adapted to automatically change the position of said piston within said cylinder in dependence on the pressure conditions within said cylinder and for the purpose of changing the space available for combustion in said cylinder in dependence on the pressure conditions of the air supplied to said cylinder and for maintaining said pressure.

2. In a united reciprocating internal combustion and compressor engine, a plurality of cylinder units, each unit comprising a compressor and a power cylinder, a floating piston operating in each of said cylinder units and comprising a power piston operating in said power cylinder and a compressor piston operating in said compressor cylinder, means interconnecting the floating pistons of two different cylinder units and adapted to assure countermovement of the interconnected pistons and comprising means for changing the position of said interconnected floating pistons at the outer dead center position thereof to a smaller extent than the position is changed at the inner dead center position when the forces acting on said pistons are changed.

3. In a united reciprocating internal combustion and compressor engine, a plurality of cylinder units, each unit comprising a power cylinder extending at both ends into a compressor cylinder, a pair of floating pistons operating in each of said cylinder units, and hydraulic couplings connected to all of said floating pistons and pairwise interconnecting those of said floating pistons which are in different cylinder units and those of said floating pistons which are in the same unit for assuring true countermovement of the interconnected pistons.

4. In a united reciprocating internal combustion and compressor engine, a plurality of cylinder units, each unit comprising a compressor and a power cylinder, a floating piston operating in each of said cylinder units and comprising a power piston operating in said power cylinder and a compressor piston operating in said compressor cylinder, a hydraulic coupling containing an operating medium interconnecting the floating pistons of at least two different cylinder units, pressure responsive means connected with said coupling and at least one of said cylinder units and being adapted to increase the content of operating medium of said coupling and to thereby simultaneously move said interconnected floating pistons further into said power cylinder and to decrease the contents of operating medium of said coupling and to thereby simultaneously move said interconnected floating pistons further into

said compressor cylinder for the purpose of increasing and decreasing the space available for combustion in said power cylinder for obtaining best operating efficiency at all load conditions and for controlling the movements of said floating pistons and assuring safe operation.

5. In a united reciprocating internal combustion and compressor engine, a plurality of cylinder units, each unit comprising a compressor and a power cylinder, a floating piston operating in each of said cylinder units and comprising a power piston operating in said power cylinder and a compressor piston operating in said compressor cylinder, a hydraulic coupling containing an operating medium interconnecting the floating pistons of at least two different cylinder units, pressure responsive means connected with said coupling and at least one of said cylinder units and being adapted to increase the content of operating medium of said coupling and to thereby simultaneously move said interconnected floating pistons further into said power cylinder and to decrease the contents of operating medium of said coupling and to thereby simultaneously move 25 said interconnected floating pistons further into said compressor cylinder for the purpose of decreasing and increasing the space available for combustion in said power cylinder for obtaining best operating efficiency at all load conditions and for controlling the movements of said floating pistons and assuring safe operation, and control means movably associated with said pressure responsive means and movably connected with said interconnected floating pistons and being also adapted to increase and decrease the content of operating medium of said coupling and to thereby counteract the action of said pressure responsive means and prevent excessive change of position of said interconnected floating pistons.

40 6. In a united reciprocating internal combustion and compressor engine, a plurality of cylinder units, each unit comprising a power cylinder extending at both ends into a compressor cylinder, a pair of floating pistons operating in each of said cylinder units, and hydraulic couplings interconnecting those of said floating pistons which are located in different cylinder units for synchronizing their movements, and other hydraulic couplings interconnecting those of said floating pistons which make up one pair and operate in the same cylinder unit for assuring true countermovement of said floating pistons which are in the same cylinder unit.

7. In a united reciprocating internal combustion and compressor engine, a cylinder unit comprising a power cylinder and two compressor cylinders connected thereto, a pair of floating pistons located in said cylinder unit, each floating piston comprising a compressor piston operating in one of said compressor cylinders and a power piston operating in said power cylinder, and a hydraulic coupling interconnecting said floating pistons for synchronizing and assuring true countermovement of said floating pistons.

45 8. In a united reciprocating internal combustion and compressor engine, a central combustion cylinder extending at both ends into a compressor cylinder, a pair of countermoving floating pistons operating in said cylinder, each floating piston comprising a compressor piston operating in one of said compressor cylinders and a power piston operating in said combustion cylinder, valve means attached to said compressor cylinders and adapting said compressor pistons to carry out a compression stroke while said power

5 pistons carry out an expansion stroke, means operatively connected to said floating pistons and being adapted to automatically change the position of said floating pistons at the end of the compression stroke of said compressor piston to a smaller extent than the position of the associated power piston is changed at the end of the compression stroke of said power piston when the forces acting on said pistons are changed.

9. In a united reciprocating internal combustion and compressor engine, a combustion cylinder extending at one end into a compressor cylinder, a floating piston in said cylinder, said floating piston comprising a compressor piston operating in said compressor cylinder and a power piston in said combustion cylinder, pressure responsive means operatively associated with said floating piston and said compressor cylinder and being adapted to automatically move said floating piston further into said compressor cylinder upon an increase of the pressure of the medium compressed in said compressor cylinder and further out of said compressor cylinder upon a decrease of the pressure of the medium compressed in said compressor cylinder for maintaining the pressure of said medium.

10. In a united reciprocating power and compressor engine, a power cylinder extending at one end into a compressor cylinder, a floating piston in said cylinder, said floating piston comprising a compressor piston operating in said compressor cylinder and a power piston in said power cylinder, pressure responsive means operatively associated with said floating piston and said power cylinder and being adapted to automatically move said floating piston further into said compressor cylinder upon an increase of the pressure in said power cylinder and further out of said compressor cylinder upon a decrease of the pressure in said power cylinder for controlling the pressure conditions in said power cylinder.

11. In a united reciprocating internal combustion and compressor engine, a combustion cylinder extending at one end into an air compressor cylinder, a floating piston in said cylinder, said floating piston comprising a compressor piston operating in said compressor cylinder and a power piston in said combustion cylinder, an air conduit connecting said compressor cylinder and said combustion cylinder, pressure responsive means operatively associated with said floating piston and adapted to automatically move said floating piston further into said compressor cylinder upon an increase of the pressure of the combustion air supplied to said combustion cylinder and further out of said compressor cylinder upon a decrease of the pressure of the combustion air supplied to said combustion cylinder for controlling the combustion air pressure and the movement of said floating piston.

12. In a united reciprocating power and compressor engine, a power cylinder extending at one end into a compressor cylinder, a floating piston in said cylinder, said floating piston comprising a compressor piston operating in said compressor cylinder and a power piston in said power cylinder, an exhaust conduit connected with said power cylinder, pressure responsive means operatively associated with said floating piston and said exhaust conduit and being adapted to automatically move said floating piston further into said compressor cylinder upon an increase of the pressure of the medium leaving said power cylinder and further out of said compressor

cylinder upon a decrease of the pressure of the medium leaving said power cylinder for controlling the pressure of the medium leaving said power cylinder.

5 13. In a united reciprocating internal combustion and compressor engine, a combustion cylinder extending at one end into a compressor cylinder, a floating piston in said cylinder, said floating piston comprising a compressor piston operating in said compressor cylinder and a power piston in said combustion cylinder, means adapted to substantially maintain the position of said pistons at the end of the compression stroke of said compressor piston when the position of 10 said floating piston at the other end of its stroke is changed due to a change of the forces acting on said floating piston for substantially maintaining the clearance in said compressor cylinder independent of changes of the position of 15 the power piston at the end of the compression stroke of said power piston.

14. In a united reciprocating internal combustion and compressor engine, a combustion cylinder extending at one end into a compressor cylinder, a floating piston in said cylinder, said floating piston comprising a compressor piston operating in said compressor cylinder and a power piston in said combustion cylinder, means adapted to adjustably maintain the position of 20 said pistons at the end of the compression stroke of said compressor piston when the position of said floating piston at the other end of its stroke is changed due to a change of the forces acting on said floating piston for adjustably maintaining 25 the clearance in said compressor cylinder independent of changes of the position of the power piston at the end of the compression stroke of 30 said power piston.

15. In a united reciprocating internal combustion and compressor engine, a plurality of cylinder units, each unit comprising a compressor and a power cylinder, a floating piston operating in each of said cylinder units and comprising a power piston operating in said power cylinder and a compressor piston operating in said compressor cylinder, said compressor piston carrying out a compression stroke when the power piston directly associated therewith makes an expansion stroke, means interconnecting the floating pistons of a plurality of different units and adapted to 40 assure countermovement of the interconnected pistons and to transmit the power of a power piston which is not used up by its associated compressor piston to the interconnected floating pistons said means comprising means adapted to substantially maintain the position of said floating pistons at the outer end of their strokes when the position of said pistons is changed at the inner end of their strokes due to a change of the forces acting on said pistons for the purpose of 45 substantially maintaining the clearance in all said compressor cylinders independent of variations of the end positions of said power pistons at the end of the compression strokes of said power pistons.

65 16. In a united reciprocating internal combustion and compressor engine, a plurality of cylinder units, each unit comprising a compressor and a power cylinder, a floating piston operating in each of said cylinder units and comprising a power piston operating in said power cylinder and a compressor piston operating in said

compressor cylinder, a hydraulic coupling containing an operating medium and interconnecting the floating pistons of at least two different cylinder units, means operatively connected with one of said cylinders and being responsive to the 5 pressure therein and being adapted to increase the content of operating medium of said coupling upon a decrease of said pressure and to decrease the content of said coupling upon an increase of said pressure and to thereby simultaneously change the position of the interconnected floating pistons in dependence on the pressure in one of said cylinders for controlling said pressure and the operation of said floating pistons. 15

17. In a united reciprocating internal combustion and compressor engine, a plurality of cylinder units, each unit comprising a compressor and a power cylinder, a floating piston operating in each of said cylinder units and comprising a power piston operating in said power cylinder and a compressor piston operating in said compressor cylinder, a hydraulic coupling containing an operating medium which interconnects the floating pistons of at least two different cylinder 20 units, control means operatively connected with one of said cylinders and being responsive to the pressure therein and being adapted to increase the content of operating medium in said coupling upon a decrease of said pressure and to decrease 25 the content of said coupling upon an increase of said pressure and to thereby simultaneously change the position of the interconnected floating pistons in dependence on the pressure in one of said cylinders for controlling said pressure 30 and the operation of said floating pistons, and a two-arm lever operatively connected at its ends to and being oscillated by the floating pistons interconnected by said hydraulic coupling and having a fulcrum which is carried by said means 35 40 and is adapted to operate said means for making said means also responsive to the position of said floating pistons for counteracting excessive actions of said control means.

18. In a united reciprocating internal combustion and compressor engine, a plurality of cylinder units, each unit comprising a compressor and a power cylinder, a floating piston operating in each of said cylinder units and comprising a power piston operating in said power cylinder 45 and a compressor piston operating in said compressor cylinder, a hydraulic coupling containing an operating medium which interconnects the floating pistons of at least two different cylinder units, control means operatively connected with 50 one of said cylinders and being responsive to the pressure therein and being adapted to increase the content of operating medium of said coupling upon a decrease of said pressure and to decrease the content of said coupling upon an 55 increase of said pressure and to thereby simultaneously change the position of the interconnected floating pistons in dependence on the pressure in one of said cylinders for controlling said pressure and the operation of said floating 60 pistons, said control means comprising means which are connected with and responsive to the movements of said interconnected floating pistons, said last mentioned means being adapted 65 to counteract the actions of said control means 70 and to prevent excessive action thereof.

HANS STEINER.
